UNITED STATES PATENT OFFICE.

ELMER N. STACY, OF MINNEAPOLIS, MINNESOTA, ASSIGNOR TO DECARIE INCINERATOR COMPANY, OF MINNEAPOLIS, MINNESOTA, A CORPORATION.

INCINERATOR.

1,315,582.

Specification of Letters Patent. Patented Sept. 9, 1919.

Application filed May 10, 1915. Serial No. 27,237.

To all whom it may concern:

Be it known that I, ELMER N. STACY, citizen of the United States, resident of Minneapolis, county of Hennepin, State of Minnesota, have invented certain new and useful Improvements in Incinerators, of which the following is a specification.

The object of my invention is to provide improved means for utilizing a forced draft 10 to be directed through the grate and combustion chamber of the incinerator, with improved means for pre-heating the air before reaching said chamber.

A further object is to provide improved 15 means for applying a suction or induced draft through the flues leading from the combustion chamber, these draft appliances being active or inactive, as desired, and operable independently of one another.

20 A further and particular object is to provide means for introducing a volume of pure air into the products of combustion flue to mix with the hot gases and promote and accelerate the combustion thereof.

25 The invention consists generally in various constructions and combinations, all as hereinafter described and particularly pointed out in the claims.

In the accompanying drawings forming 30 part of this specification,

Figure 1 is a longitudinal, vertical sectional view through an incinerator embodying my invention,

Fig. 2 is a horizontal sectional view, showing the position of the pre-heating appliance with respect to the rest of the apparatus,

Fig. 3 is a vertical sectional view on the line $x-x$ of Fig. 1, and $z-z$ of Fig. 2, and

40 Fig. 4 is a similar view on the line $y-y$ of Fig. 1, also looking in the direction of the arrow.

In the drawing, 2 represents the wall of the building in which the incinerating apparatus is located, and 3 is the incinerator proper, having a combustion chamber 4 wherein the header 5 and circulating pipes 6 are arranged. Beneath the header are the grates 7 having pits 8, 9 and 10 beneath them, separated by partitions or walls 11. A floor 12 forms the bottom of these pits and beneath this floor I provide a chamber 13.

Adjacent to the combustion chamber is a chamber 14 wherein the pre-heater is arranged, composed of flue sheets 15 and flues

16 between these sheets. A cold air intake trunk 17 leads through the wall of the building to the space between the flue sheets 15 and a trunk 18 communicates with this space and with a force fan 19 which in turn communicates through a passage 20 with the chamber 13 (Fig. 3). By means of this fan the cold air is drawn in through the pipe 17, circulates among the flues 16 and is delivered in an expanded heated condition to the chamber 13. From this chamber pipes 21 extend to the pit 10 and trunks 22 lead from the chamber 13 to the pits 8 and 9 and through these pipes and trunks a volume of heated air will be forced through the grate bars and into the combustion chamber to form a forced draft and hasten combustion. I also provide a pipe 22' leading upwardly from the passage 20 and having depending ends 22'' for discharging 70 heated air into the mixing chamber 23 adjacent to the passage through which the products of combustion flow from the chamber 4. This heated air mixes with the products of combustion in the chamber 23 and 80 promotes and accelerates the combustion of the heated gases. I regard this arrangement for delivering the volume of air to the flue and the hot gases as an important feature of my invention.

85 A mixing chamber 23 is provided in the rear of the combustion chamber and communicates therewith through a passage 24, and a checkered wall 25 separates the chamber 23 from the chamber 26. The checkered wall will become incandescent in the operation of the incinerator and aid materially in accelerating combustion of the hot gases mixed with the fresh air and coming in contact with this wall. From this chamber 26 90 a flue 27 having a damper 28 therein opens into a flue 34 which leads to the stack flue 38. A passage 30 (Fig. 4) leads from the chamber 26 into the chamber 14, sufficient space being provided in the bottom of this chamber to allow precipitation of ashes and soot. The gases and products of combustion from the chamber 14 pass through the flues 16 to a chamber 31 (Figs. 2 and 4) above these flues which communicates through a trunk 100 32 with a suction or induced draft fan 33 from which a trunk 34 leads to the stack flue 38 of the stack 29. A valve 35 is provided in the trunk 32 for shutting off the passage therethrough, and a trunk 36 (Fig. 110

2) leads from the chamber 31 to the stack-flue 38 of the stack and is provided with a valve 37 which, when opened, allows the products of combustion to flow directly to 5 the stack through the stack-flue 38 without passing to the fan 33.

With the foregoing described apparatus I am able to utilize the hot gases for pre-heating the incoming cold air before its delivery 10 to the lower part of the combustion chamber and at the same time I can deliver a quantity of this air to the products of combustion flue to mix with the gases therein and effect a more perfect combustion thereof. I am 15 also able by means of the suction fan to establish an induced draft and accelerate the flow of the products of combustion from the incinerator. When preferred, the natural draft may be utilized, the products of combustion 20 passing directly to the stack.

In various ways the details of construction herein shown and described may be modified and still be within the scope of my invention.

25 I claim as my invention:

1. An incinerator having a combustion chamber, a mixing chamber, and an outlet from the former discharging into the latter, a preheater having a cold air intake, a blast 30 fan mounted to receive air from said preheater, an air trunk leading from said fan to the lower portion of said combustion chamber and having a branch leading to said mixing chamber for mixing air with the 35 heated gases, a flue, having a damper, in communication with the mixing chamber and leading to a stack, and a valve controlled exit flue in indirect communication with the mixing chamber through the preheater.

40 2. An incinerator having a combustion chamber, a mixing chamber, and an outlet from the former discharging into the latter, a preheater having a cold air intake, a blast fan mounted to receive air from said preheater, an air trunk leading from said fan to the lower portion of said combustion chamber and having a branch leading to 45 said mixing chamber for mixing air with the heated gases, a flue, having a damper, in communication with the mixing chamber and leading to a stack, a valve controlled exit flue in indirect communication with the mixing chamber through the preheater and 50 provided with a suction fan.

exit flue in indirect communication with the mixing chamber through the preheater, and a suction fan for said exit flue.

3. An incinerator having a combustion 55 chamber, a mixing chamber, and an outlet from the former discharging into the latter, a pre-heater having a cold air intake, a blast fan mounted to receive air from said pre-heater, an air trunk leading from said fan 60 to the lower portion of said combustion chamber and having a branch leading to said mixing chamber for mixing air with the heated gases, a checkered wall in said mixing chamber, a flue having a damper and in communication with the mixing chamber for the direct passage of products of combustion to a stack without passing through the pre-heater, an exit flue in indirect communication 65 with the mixing chamber through the preheater, and a suction fan for said exit flue.

4. An incinerator having a combustion chamber, an outlet for the products of combustion and a mixing chamber into which 70 the products of combustion discharge, a pre-heater in communication with the mixing chamber and having a cold air intake, a blast fan mounted to receive air from said pre-heater, an air trunk leading from said fan 75 to the lower portion of said combustion chamber, and a branch pipe leading from said air trunk and having downwardly turned end portions for discharging heated air into said mixing chamber.

80 5. An incinerator having a combustion chamber, a mixing chamber, and an outlet from the former into the latter, a preheater in communication with the mixing chamber, a blast fan and air conduit for transmission 85 of air from the preheater to the lower portion of the combustion chamber, a flue, having a damper, in communication with the mixing chamber and leading to a stack, a flue, having a damper, and leading from the preheater to a stack, and a valve controlled 90 exit flue in indirect communication with the mixing chamber through the preheater and provided with a suction fan.

In witness whereof, I have hereunto set 1 my hand this 4th day of May 1915.

ELMER N. STACY.
